UNITED STATES PATENT OFFICE.

HENRY W. O'DOWD, OF PEEKSKILL, NEW YORK, ASSIGNOR TO WILLIAM M. CRANE COMPANY, A CORPORATION OF NEW YORK.

PRESSURE-CONTROLLED VALVE.

1,053,315.

Specification of Letters Patent. Patented Feb. 18, 1913.

Application filed April 5, 1909. Serial No. 487,862.

To all whom it may concern:

Be it known that I, HENRY W. O'DOWD, a citizen of the United States, and a resident of Peekskill, county of Westchester, 5 and State of New York, have invented certain new and useful Improvements in Pressure-Controlled Valves, of which the following is a specification.

My invention relates to valve mechanisms, 10 and more particularly to valves for automatically controlling the flow of one fluid by variations in the pressure of another, as for automatically controlling the supply of fuel to steam generator burners using hydrocarbon fuels by variations in the pressure of the steam.

Objects of the invention are to provide an improved construction of the character referred to which shall be highly sensitive to 20 variations in the pressure of the controlling fluid; which shall be proof against leakage of either fluid; which shall provide that the minimum of fluid remains in the valve mechanism when the valve is in its closed 25 position; and which shall be simple and durable in construction, with parts few, easily accessible and compactly arranged, and economical and highly efficient in operation. These and other objects of the invention will in part be obvious and in part 30 be made clear from the following description.

The invention consists in the novel parts, improvements, combinations, and features 35 of construction herein shown and described.

The accompanying drawing, which is referred to herein and forms a part hereof, illustrates an embodiment of the invention, the same serving in connection with the description herein to explain the principles 40 of the invention.

The drawing is a vertical central section of an automatic fuel-controlling valve combined with steam pressure controlling means 45 constructed in accordance with my invention.

Referring now in detail to the drawing, the embodiment of the invention illustrated comprises a casing 1 adapted to be secured 50 in communication with a source of fuel supply, as a gas pipe, and containing preferably in its lower portion a fuel or gas passage which, as shown, is divided by a diaphragm 2 into compartments 3 and 4.

A feature of the invention relates to the

means for establishing and interrupting communication between said compartments. In the embodiment of the invention illustrated ports 5 and 6 are preferably formed in the respective upper portions of these 60 compartments, a flange 7 preferably outlining one of said ports and extending slightly above the port and forming a valve seat. As shown, also, a flange 8, preferably with its upper surface in the same horizontal 65 plane as the upper surface of the flanged valve seat 7, encircles the casing 1 on its inner face.

Means are provided to operate on the valve seat 7 and thus establish and cut off 70 the supply of gas or other fuel passing through the mechanism. While said means may be formed and arranged in various ways and of different materials, preferably it consists of a member consisting of a valve 75 portion proper, and an extension thereof, the whole forming a diaphragm 10, preferably of flexible material, such as leather, which extends to and is seated upon the flange 8, where, in the embodiment illustrated, it is tightly engaged by a cap piece 12 of the casing, said cap piece, as shown, being exteriorly threaded to correspond with the interior threading of that part of the casing. It will be seen that said valve 85 diaphragm forms the upper wall of a chamber which communicates with said compartments 3 and 4 and which varies in volume with the operation of the valve, whose flexibility permits of its operation, and that 90 said chamber, when the valve is in its seated position, is of very slight volume, thus preventing the accumulation of gas and air in any material amount in said valve chamber and thus obviating the evil effects of such 95 accumulation, such as back firing. It will also be noted that as said diaphragm is tightly fastened to the flange 8, leakage into the casing above said valve is prevented. Furthermore, as will be apparent, the valve 100 is kept always flexible and in good order by its operation, and ridges and indentations, which might in time permit leakage, are avoided.

According to another feature of the invention, means are provided for automatically operating the valve 10 in unison with the variations in pressure of the steam in the generator; and, while so far as certain 105 features of the invention are concerned any 110

suitable means may be provided for this purpose; preferably and as shown, in a chamber 15 formed in the upper part of said casing is arranged a diaphragm 16, preferably 5 of a flexible material adapted to resist corrosion by the steam. As shown, also, said diaphragm extends entirely through said chamber 15 and is seated upon the periphery of the casing, where it is tightly engaged by a second cap piece 17 which is, as shown, bolted to and forms part of the casing, thus making a joint proof against steam leakage. The chamber 15 communicates 10 through a pipe 18 with the steam generator, 15 not shown.

It will be apparent that as the pressure of the steam in the generator varies, so will the pressure vary upon the diaphragm 16. Suitable connecting means are therefore 20 provided between the diaphragm 16 and the valve diaphragm 10 so that this variable steam pressure upon the diaphragm 16 may be communicated to said valve 10 that the latter may be operated in unison with 25 the movement of the diaphragm 16. In the embodiment of the invention illustrated a stem 19 is rigidly secured to the diaphragm 16 in a manner to prevent leakage and extends through the casing 1, passing through 30 the port 5 and chamber 4 and emerging from the bottom of the casing. The valve 10 is suitably and securely fastened to said stem 19 with a vapor-proof joint and, preferably, a rigid member 20 lies above and 35 holds the valve, when in its seated position, more closely to its seat. It will be apparent that as the diaphragm 16 is depressed by the pressure of the steam, the valve 10 will also be depressed toward or to the valve 40 seat 7. In order however that the valve may be kept in a normally open position or unseated upon the reduction of the steam pressure, suitable means are provided which, preferably and as shown, consist of a spring 45 21 coiled about the stem 19 outside and beneath the casing 1, said spring being engaged by a yoke 22 suitably secured to said casing and by a collar 23 upon the stem 19. In order that the spring 21 may be controlled 50 in its operation, said collar 23 is threaded upon said stem 19 and may be adjusted at will to determine the tension of the spring and thus the extent to which the valve 10 will be opened thereby. It will be 55 seen that when the pressure in the generator reaches a predetermined point, the pressure on the diaphragm 16 will overcome the force of the spring 21 and close the valve 10; when the pressure is reduced, the spring will 60 automatically open the valve.

It will be seen that by reason of the construction shown and described a form of automatic fuel valve mechanism is provided which is simple, efficient and safe, and particularly well adapted for steam generator

burners using gas or other fluid fuel. Other advantages will be apparent to those skilled in the art.

It is to be understood that my invention in its broader aspects is not limited to the precise construction shown nor to any particular construction by which the same has been or may be carried into effect, as many changes may be made in the details of the parts without departing from the main principles of the invention and without sacrificing its chief advantages.

I claim:

1. An automatic valve-mechanism including in combination, a casing, a gas-passage 80 extending therethrough, a plurality of chambers in said casing in alignment with said passage, a main chamber overlying said plurality of chambers, a diaphragm interposed between said main chamber and said 85 plurality of chambers and adapted to control communication between said plurality of chambers, a pressure-chamber disposed remotely from said main chamber, a diaphragm mounted in said pressure-chamber, a connection between the diaphragm therein and said first-mentioned diaphragm and adapted to position the latter in relation to the plurality of chambers, and means forming a leakage-tight separation between the main 90 chamber and the pressure-chamber.

2. An automatic valve-mechanism for a steam generator including in combination, a casing, a gas-passage therethrough, a partition dividing said passage into a plurality 100 of chambers, ports formed in said chambers, a main chamber overlying said first-mentioned chambers, a valve-diaphragm arranged in said main chamber and adapted to operate on one of said ports, a pressure-chamber attached to said casing, a diaphragm located in said pressure-chamber and adapted to be operated by pressure within the pressure-chamber, a stem connecting said diaphragms, and a leakage-tight joint between the main and pressure-chambers whereby fluid within the pressure-chamber is prevented from entrance into the main chamber, and means for normally maintaining said valve-diaphragm in unseated position.

3. A valve-mechanism including in combination, a casing provided with inlet and outlet openings, a pressure-chamber separably mounted upon said casing, a pair of chambers formed in said casing, a main chamber also formed in said casing and closed against passage of a fluid either from said pair of chambers or from said pressure-chamber, a pair of diaphragms arranged respectively in the pressure and main-chambers and connected for co-action, one of said diaphragms being disposed between the main chamber and the pair of chambers, a port between the main chamber and the in-

let opening, and means in the casing for maintaining the diaphragm in the main chamber normally unseated from said port.

4. A valve-mechanism including in combination, a casing, a gas-passage therethrough, a partition dividing said passage into a plurality of chambers, ports formed in said chambers, a main chamber overlying said plurality of chambers, a diaphragm for controlling one of said ports and adapted to close said main chamber against passage thereinto of any fluid flowing through said casing, a pressure-chamber overlying said main chamber and independent thereof and closed against passage of any fluid thereto from into said main chamber, a diaphragm located in said pressure-chamber, a stem connecting said diaphragms for co-action, and means connected to said stem and supported on said casing for normally holding one of said diaphragms in a raised position.

5. A gas-valve mechanism including in combination, a casing provided with inlet and outlet openings, a partition formed in

25 said casing and dividing the same into a pair of chambers communicating by a port, a diaphragm seated on said port, a cap-piece secured to the casing and engaging said diaphragm to hold the same in operative position and, with said diaphragm, forming 30 a main chamber, a pressure-chamber attached to said cap-piece and closed against passage of fluid therefrom into said main chamber, a diaphragm located in said pressure-chamber, a stem extending between 35 said diaphragms for effecting their co-action, and adjustable means supported by said casing and attached to said stem for normally holding the first-mentioned diaphragm unseated from said port.

40 In testimony whereof, I have signed my name to this specification, in the presence of two subscribing witnesses.

HENRY W. O'DOWD.
